(57) **CLAIM**

The ornamental design for an electrophoresis device, as shown and described.

DESCRIPTION

FIG. 1 is a front and side perspective view of an electrophoresis device for performing electrophoresis of nucleic acids, and visualization, imaging and/or analysis thereof, according to our design;

FIG. 2 is a front perspective view of the electrophoresis device of FIG. 1;

FIG. 3 is a back perspective view of the electrophoresis device of FIG. 1;

FIG. 4 is a right side perspective view of the electrophoresis device of FIG. 1;

FIG. 5 is a left side perspective view of the electrophoresis device of FIG. 1;

FIG. 6 is a top side perspective view of the electrophoresis device of FIG. 1; and,

FIG. 7 is a bottom perspective view of the electrophoresis device of FIG. 1.

Portions of the electrophoresis device shown in broken lines form no part of the claimed design.
